tion of Pennsylvania

Application December 23, 1933, Serial No. 50,204

Term of patent 7 years

To all whom it may concern:

Be it known that I, NICHOLAS KOPP, a citizen of the United States, residing at Pittsburgh, in the county of Allegheny, and State of Pennsylvania, have invented a new, original, and ornamental Design for a Lighting Fixture Bowl or Similar Article, of which the following is a specification, reference being had to the accompanying drawing, forming part thereof.

In the drawing:

The figure is a perspective view of a lighting fixture bowl or similar article, showing my new design.

I claim:

The ornamental design for a lighting fixture bowl or similar article, as shown.

NICHOLAS KOPP.
